UNITED STATES PATENT OFFICE.

EDWIN WALKER, OF ERIE, PENNSYLVANIA.

DESIGN FOR A CORKSCREW-HEAD.

SPECIFICATION forming part of Design No. 31,505, dated September 12, 1899.

Application filed August 9, 1899. Serial No. 726,721. Term of patent 14 years.

To all whom it may concern:

Be it known that I, EDWIN WALKER, a citizen of the United States, residing at Erie, in the county of Erie and State of Pennsylvania, have invented a certain new and original Design for Corkscrew-Heads; and I do hereby declare the following to be a full, clear, and exact description of the invention, such as will enable others skilled in the art to which it applies to make and use the same, reference being had to the accompanying drawings, and to the letters of reference marked thereon, forming part of this specification.

The leading features of my design consist, substantially, of the shape and configuration of a corkscrew-head, comprising, substantially, a corkscrew-head having the ring forming the base thereof cut away, so as to leave an opening therein, and having a hook projecting from the collar forming the upper part of the head immediately above the opening in the base-ring, and also in having a blade projecting downward from the base opposite the opening therein.

Figure 1 shows a perspective view of a corkscrew-head embodying my design. Fig. 2 shows a vertical section of the same. Fig. 3

shows a plan view of the lower end of the same.

In the drawings, A is the collar of the head, 30 and B the base-ring thereof, and D D D curved arms joining the collar A and the base B. One side of the base-ring B is cut away for about one-third of its circumference, and on the collar A there is an arm E, projecting 35 laterally directly over the opening in the base B and having a downwardly-projecting hook e on the end thereof. On the periphery of the base-ring B, directly opposite the opening therein, there is a downwardly-projecting 40 blade F, and on the inside of the lower surface of the base-ring B there is an annular concave surface b.

Having thus described my design, what I claim is—

The design for a corkscrew-head, substantially as shown and described.

In testimony whereof I affix my signature in presence of two witnesses.

EDWIN WALKER.
